DESIGN.

—o—

J. SPRING.

CARPET.

No. 17,785.

Patented Oct. 11, 1887.

UNITED STATES PATENT OFFICE.

JOHN SPRING, OF HIGH BRIDGE, NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,785, dated October 11, 1887.

Application filed August 30, 1887. Serial No. 248,321. Term of patent 3½ years.

To all whom it may concern:

Be it known that I, JOHN SPRING, of Claremont, High Bridge, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design is composed of a large number of leaf and flower forms of different sizes and

shapes massed together in a compact manner, so as to almost entirely cover the face of the carpet. The most prominent leaves and flowers are of a circular or oval outline with their edges more or less regularly indented. Many of the spaces between the larger figures are filled with small circular flowers, which form the less prominent parts of the design.

What I claim as new, and desire to secure by Letters Patent, is—

The design for carpets, consisting of the design substantially as shown.

JNO. SPRING.
